CESARE BARBIERI AND PAUL CARPENTER, OF CHICAGO, ILLINOIS.

INVERTED INCANDESCENT MANTLE.

1,263,732.

Specification of Letters Patent. Patented Apr. 23, 1918.

Application filed August 29, 1910, Serial No. 579,452. Renewed September 15, 1917. Serial No. 191,630.

To all whom it may concern:

Be it known that we, CESARE BARBIERI, a subject of the King of Italy, and a resident of Chicago, in the State of Illinois, United States of America, and PAUL CARPENTER, a citizen of the United States, and a resident of Chicago aforesaid, have invented certain new and useful Improvements in Inverted Incandescent Mantles, of which the following is a specification.

Our present invention relates to incandescent lighting mantles, and more particularly to mantles used in connection with hydro-carbon gas, and has especial reference to the provision of an improved mantle of the so-called incandescent type.

The principal objects of our present invention are the provision of an improved mantle characterized as above noted which may be formed from a single flat piece of material without stitches or seams; the provision of an improved mantle wherein the hemispherical portion which is the source of the greatest volume of available light rays is of substantially uniform thickness throughout, whereby a superior volume of light and greater evenness in the quality thereof may be attained than in others known to us; the provision of improved means for stiffening the mantle; the provision of improved means for attaching the mantle to the supporting base which is required in the use of the mantle; the provision of an improved form of supporting base adapted to hold the mantle securely, to maintain its original symmetrical form and one having simple means for the attachment of the mantle thereto; the provision of a mantle which is not only superior in light giving properties, but also most inexpensive in manufacture and may be made in extraordinarily large sizes, together with such other objects as may hereinafter appear.

In all mantles of the inverted type known to us, the dome of which is desirably closed, closure is effected by sundry stitching and cutting operations, involving the use of expensive machinery, considerable hand labor and waste of material, distortion of the mantle in the course of manufacture owing to the extreme flexibility of the material of which it is made, certain complications in the method of fixing the mantle in position upon the kaolin base which supports it, and

creases, folds, and bunching of the material making it dense and presenting lines of cleavage whereby it is weakened both in respect to light giving properties and strength at the points where greatest efficiency as to both is desirable, not only making it expensive on account of lack of longevity but on account of the greater quantity of gas required for incandescence.

In overcoming the disadvantages referred to and attaining the objects stated, as well as certain further benefits and advantages to be below disclosed, we have provided the construction illustrated in the accompanying drawing, wherein—

Figure 1 is a plan view of textile fabric webbing used by us in the manufacture of our improved mantle;

Figs. 2 and 3 are respectively a plan and an elevational view of the kaolin supporting base used in connection with our improved mantle.

Figs. 4, 5 and 6 are respectively a top plan, an elevational, and a sectional view of the completed mantle, Fig. 6 being taken on the line drawn VI—VI of Fig. 4.

Referring first to Figs. 1, 2 and 3, it is to be noted that the mantles are preferably formed from circular pieces of fabric 10 in order that the most economical use may be made of the fabric in cutting, and to avoid waste and facilitate trimming when the mantle is put into position about the supporting base 11, (now to be described) burned, and treated by immersion in collodion or other suitable protecting material preparatory to shipping and use in the customary manner.

Referring now more particularly to Figs. 2 and 3, it will be observed that the base 11 comprises an annular portion 12, here shown as having a plurality of supporting arms 13, the outer surface of the base being provided with a plurality of projecting portions 14—14—14 the indentations therebetween as well as such portions 14 being preferably rounded, also the portions 14 being indented or notched, as is clearly to be seen at 16 (Fig. 3) to receive a binding cord 17, all for purposes to be below described.

In forming the incandescent portion of the mantle, it will be observed on referring to Figs. 4, 5 and 6, the fabric 10 is drawn into a hemispherical dome-like portion 18 and the excess cloth formed into a number

of corrugations 19 which are fitted about and into the rounded portions 14 and 15 of the base, and the binding cord 17 drawn tightly thereabout and into the notches, 16, 5 and then knotted, whereby the parts of the completed mantle are firmly held from movement relatively to each other.

It will thus be noted that we have provided a construction of mantle wherein no 10 stitching of the fabric is required, no seams are present to cause inequalities in the diffusion of the light, no bunching of material is present to cause strains on any portion of the mantle, no distortion of the mantle 15 owing to imperfections in sewing is possible; one wherein practically all of the material of the fabric is available for incandescence and a greater superficial area of incandescent surface is presented to the action of the 20 burning gas, one which, owing to the presence of the corrugations, is quite stiff and at the same time not so liable to breakage as those in which there are seams, stitching or bunching, causing unequal strains on various 25 parts of the mantle, and one which being formed from a piece of webbing having no projecting portions, may be dipped and ironed if desired after forming, instead of before forming with much greater facility 30 than others known to us.

It will be particularly noted that the dome portion 18 is entirely free from not only 35 seams and stitching, but from all inequalities whatsoever, thus gaining the highest efficiency in light and also avoiding the lines of cleavage along which it is found in practice that mantles most frequently break.

Having thus described our invention and 40 illustrated its use, what we claim as new and desire to secure by Letters Patent is the following:

1. As an article of manufacture, a dome shaped mantle formed from flat fabric without seams and provided with corrugations 45 tapering toward the end thereof, and stopping short of the terminal portion thereof,

and a smooth rounded terminal portion of uniform thickness throughout.

2. As an article of manufacture, a dome shaped mantle formed from flat fabric without 50 seams and provided with a plurality of substantially parallel longitudinal tapering corrugations stopping short of the terminal portion thereof, and a smooth rounded terminal portion of uniform thickness throughout. 55

3. As an article of manufacture, a seam- 60 less cylindrical mantle having an open top and a dome-shaped base of substantially uniform thickness throughout, the said cylindrical portion being provided with stiffening corrugations and the dome portion being plain.

4. A mantle comprising, in combination with a supporting base and binding means, 65 a piece of substantially flat radially corrugated fabric of substantially the same texture throughout bent along the corrugations and bound to said base whereby a dome shaped end is formed by such bending and 70 binding.

5. The process of making mantles which consists in corrugating a piece of substantially flat fabric radially, bending it along the corrugations, fastening the corrugated 75 portion to a supporting base, and then burning the mantle thus formed over a forming flame to set the fabric in its final shape.

6. As an article of manufacture, a dome shaped mantle of substantially the same texture throughout formed of a piece of substantially flat fabric provided with stiffening corrugations tapering toward the dome. 80

In testimony whereof we have hereunto signed our names in the presence of the two 85 subscribed witnesses.

CESARE BARBIERI.
PAUL CARPENTER.
